GUIDING MEANS FOR ROLLING MILLS

Application filed June 15, 1928. Serial No. 285,623.

This invention relates to improvements in guiding means for rolling mills such as those employed in steel mills and the like for reducing hot ingots or slabs to the form of bars, strips or sheets. The principal object of the present invention is to provide an improved form of guiding means for properly guiding sheets, strips or the like in their travel between the reducing rolls of the mill. Although the invention may be employed with advantage in the guiding of single sheets or strips of metal, it is peculiarly adapted for use in guiding a plurality of superimposed layers of metal, known as a pack, between the reducing rolls. Where the pack is formed by doubling a partially reduced and greatly elongated flat bar or strip of metal upon itself, it is important that the upper layer of the doubled bar be maintained with its edges in exact alignment with the edges of the lower layer of the doubled bar or strip during the subsequent reduction by the finishing rolls and the guiding means of the present invention may be used efficiently for that purpose. An important object of the present invention is to provide guiding means comprising guiding rollers for engaging the edges of the advancing strips in combination with normally stationary guiding means preferably located to guide the sheet or sheets immediately before they pass between the reducing rolls. A further object of the invention is to provide improved guiding means capable of adjustment for accommodating different widths of flat bars or strips and for permitting the desired accurate spaced relation of the guiding means with respect to the edges of the strips and with respect to each other. A further object of the invention is to provide improved guiding means having parts for engaging opposite sides of the metal strips which are simultaneously adjustable by a single operating means. Other objects relate to various features of construction and arrangement which will appear more fully hereinafter.

The nature of the invention will be understood from the following specification taken with the accompanying drawings in which

one embodiment of the improved guiding means is illustrated. In the drawings,

Fig. 1 shows a somewhat diagrammatic top plan view of a rolling mill having applied thereto the guiding means of the present invention; 55

Fig. 2 shows a diagrammatic side elevation of the apparatus illustrated in Fig. 1;

Fig. 3 shows an enlarged diagrammatic side elevation of the portion of apparatus shown in Fig. 1 whereby the elongated bar is doubled upon itself preliminary to being subjected to the action of the finishing rolls. 60

Fig. 4 shows a top plan view of the improved guiding means with the uppermost reducing roller and adjacent parts of the supporting structure removed; 65

Fig. 5 shows a longitudinal section taken on the line 5—5 of Fig. 4;

Fig. 6 shows a transverse section taken on the line 6—6 of Fig. 5; 70

Fig. 7 shows a transverse section through the mill illustrating the method of driving the rollers of the guiding means;

Fig. 8 shows a somewhat diagrammatic side elevation of two pairs of reducing rolls and of the rollers embodied in the guiding means, illustrating the means for driving these guiding rollers; 75

Fig. 9 is a diagrammatic cross-sectional view illustrating the engagement with the rollers of the guiding means of the edges of the metal sheets; and 80

Fig. 10 is a detailed sectional view taken on the line 10—10 of Fig. 7. 85

For the purpose of explaining the use and operation of the improved guiding means more clearly, it has been illustrated in the accompanying drawings in connection with a particular arrangement of rolling mill apparatus wherein the original slab is doubled upon itself after being partially reduced and greatly elongated and then passed through the reducing rolls in doubled form, the improved guiding means of the present invention being located adjacent to the respective sets of reducing rolls which engage the doubled bar or strip. Of course, the guiding means constituting the present invention might be embodied in other forms of rolling 95

100

mills and adapted for use with the rolling of single sheets of metal. In the operation of the rolling mill apparatus shown in Figs. 1 and 2, the original ingots are formed into slabs preferably several feet long, two inches or more in thickness, and about four inches or more in width. These slabs are heated in a suitable furnace 15 to a temperature suitable for the subsequent rolling operation which may preferably be about 2300 degrees F. to permit the sequence of operations described in connection with the apparatus shown in the drawings. These slabs after being heated in the furnace 15 are discharged one at a time into the guide channel 16 of the rolling mill where they are engaged by the feeding rollers 17 and pass between a number of sets of reducing rolls which constitute the roughing rolls of the mill. Each slab engages the first set of roughing rolls 18 edgewise to impart a uniform width to the slab throughout its length. The slab is then turned onto its flat side and is passed between the next set of roughing rolls 19 by which the slab is partially reduced in thickness and slightly increased in width. The slab is then again returned to its edge, either automatically or by hand, and is given an edgewise pass through the set of rolls 20, following which it is returned to its flat side and further reduced in thickness by the action of the reducing rolls 21. After emerging from the reducing rolls 21, the slab is engaged by the edge rollers 22 which are mounted on vertical axes. These edge rollers are located adjacent to the last set of reducing rolls 23 which give the final reducing operation of the roughing rolls. The various horizontal rolls 18, 19, 20, 21 and 23 are driven through suitable gearing located in the boxes 24 and the shafts of this gearing are connected by bevel gears 25 with a common driving shaft 26 extending longitudinally of the mill parallel to the path of travel of the slabs being reduced. The shaft 26 is driven through a belt 27 from an electric motor 28. The vertical shafts of the edging rollers 22 are connected to a common transverse shaft 29 by suitable gearing and this shaft 29 is in turn driven by an electric motor 30.

As the partially reduced and greatly elongated sheet of hot metal emerges from the last set of roughing rolls 23, it is subjected, in this particular form of rolling mill, to a doubling operation whereby a part of the elongated strip or sheet is doubled upon the remainder. Before this doubling is effected, the top surface of the strip or top sheet is preferably covered during its travel with a suitable separating agent adapted to prevent the hot strips or sheets from welding or adhering to each other during the rolling process which follows the doubling of the strips or sheets. This agent may be sodium carbonate or other

agent distributed onto the top surface of the flat bar from a sifting box 31 located above the path of travel of the bar as shown in Figs. 1 and 2 or in any other suitable way. The method of rolling involving the use of such a separating agent is particularly described and claimed in my co-pending application Serial No. 285,621, filed June 15, 1928. As the hot bar passes beyond the sifting box 31, the forward end thereof is automatically engaged by a gripping arm 36 having a jaw 36^a at its lower end which engages the end of the bar and swings upwardly, in the manner illustrated in Fig. 3, to raise the forward end of the elongated and flattened bar out of the path of travel of the remaining portion so that the trailing portion of the bar passes beneath the gripping member 36 and thus causes the elongated bar to be doubled upon itself. As the trailing end of the elongated bar 35 reaches a point adjacent to the gripping arm 36, the operator at the side of the mill releases the forward end of the bar from the gripping jaw 36^a and allows the doubled bar to advance bodily on the underlying rollers 37. As this advance continues, the doubled end 35^a of the bar engages successive pairs of rolls 38, 39 and 40 having the rolls of each pair spaced apart in diminishing amounts so that as the doubled bar advances into the throat of these rollers, the bent end is flattened upon itself until as it emerges from the last of these flattening rollers 40, the top portion 35^b of the bar lies flat upon the underlying portion 35^c. This method of doubling the elongated bar and the apparatus for accomplishing that function are described and claimed in the co-pending application of Ralph H. Norton and William C. Fork, Serial No. 285,622, filed June 15, 1928.

As the doubled bar 35 emerges from the doubling apparatus, it is engaged by a pair of edge rollers 43 having a common driving shaft 44 which is actuated by an electric motor 45. These edge rollers serve to align the upper and lower layers of the doubled bar with each other before this bar passes into engagement with the rolls 46 by which the first step of the final reduction to sheet gauges is accomplished. After passing through the rolls 46, the doubled bar 35 passes through a number of other sets of horizontal reducing rolls 47 of which four sets are shown in the accompanying drawings. The reducing rolls 46 and 47 are adapted to effect the gradual reduction of the doubled bar or strip to the final finished gauge desired and each set of these rolls is driven through the mechanism of a gear box 48 from an electric motor 49 so that each set of reducing rolls may be actuated independently at the desired speed. Instead of employing vertical edging rollers, similar to the rollers 43 for maintaining alignment of the superimposed layers of the metal bar or strip, after

this strip has passed through the first set of finishing rolls 46, there is employed in conjunction with each of the sets of finishing rolls 47 the particular form of guiding means 50 which constitutes the improvement of the present invention. The guiding means 50 are shown more particularly in Figs. 4 to 10 inclusive of the drawings. As the forward portion of the metal bar or strip 35 advances over the guideway 16 of the reducing mill, after passing through the preliminary finishing rolls 46, it is engaged on its under side by a guide member 51 having an upper inclined face 51^a which elevates the strip 35 as it passes between the lateral blocks 52. These guide blocks are mounted to travel over the table 16^a of the guide channel 16 for purposes of adjustment in a lateral direction but they have a fixed position for a particular width of sheet being rolled. The blocks 52 are hollow and the outer vertical wall of each block is provided with a nut 53 which is threadedly engaged by the adjusting screw 54. The adjusting screw is journaled in bearings carried by the side plates 55 which are secured by bolts or studs 56 to the underside of the laterally projecting flanges of the table 16^a, as shown particularly in Fig. 6. The ends of the adjusting screw 54 have collars 57 secured thereon and one end of the adjusting screw has a squared portion 54^a adapted to be engaged by a wrench. The portions of the adjusting screw 54 which engage the nuts 53 are threaded in opposite directions so that when the adjusting screw is rotated the lateral guide blocks 52 are simultaneously adjusted toward or from each other. The guide blocks 52 are provided on their inner sides with cheek plates 58 having flanges 58^a which overlie the guide blocks and are secured thereto by studs 58^b, as shown in Fig. 4. These cheek plates are provided on their forward sides with curved surfaces 58^b which extend downwardly and merge into the downwardly and rearwardly inclined surfaces 58^c adapted to engage the forward edge of the oncoming metal strip and guide it downwardly toward the guide plate 51. The cheek plates 58 terminate at their lower portions in rearward extensions 58^d which have lower horizontal surfaces extending parallel to the top surface of the rear portion of the guide plate 51, leaving sufficient clearance for the metal strip, or the doubled metal sheet to pass therebetween, as illustrated by the dotted lines in Fig. 5. The metal strip is thus maintained in a substantially definite horizontal plane as it travels rearwardly between the guiding blocks 52. The side plates 55 between which these lateral guide blocks 52 are mounted, are preferably connected at their upper edges by a transverse tie rod 59. Each guide block 52 carries at its forward end a guide roller 60, the annular groove 60^a of which is adapted to engage one edge of the traveling metal strip or bar. These guide rollers are located in recesses 61 on the under sides of the forward ends of the guide blocks 52 and project inwardly beyond the guide blocks sufficiently to engage the edges of the metal strip, as shown in Fig. 4. The guide rollers 60 are secured on vertical shafts 62 which are journaled in the guide blocks 52 and the upper ends of these shafts 62 are connected by bevel gears 63 with other bevel gears 64 secured on a transverse shaft 65. This shaft 65 is journaled in bearings 66 carried by the guide blocks 52 and is driven in the manner hereinafter described so that it not only guides the metal strip and maintains the proper alignment of the superimposed layers thereof but also acts as a feeding means. In order that the guide blocks 52 and the guide rollers 60 may be securely held in position after they have been adjusted to bring about the desired spaced relation, each guide block 52 is provided with a clamping bolt 68 the head of which engages an undercut transverse slot 69 in the supporting guide table 60. These bolts 68 extend upwardly through holes in the guide blocks 52 and are engaged at their upper ends by a bar 70 and nuts 71 so that the guide blocks can be securely clamped in place after the adjusting screw 54 has been operated to effect a simultaneous adjustment of the two guide blocks and the two guide rollers 60 which are movable therewith.

The guiding means 50 also comprises means for engaging and guiding the strip 35 after it has passed the guiding rollers 60 and immediately before it passes between the reducing rolls 47. This additional guiding means comprises a pair of guide blocks 75 which are adjustable transversely of the path of travel of the metal strip on a guide member 76, as illustrated in Figs. 4 and 5. The guide member 76 is carried by integral brackets 77 having flanges 78 which are secured by studs 79 to the frame members 80 of the reducing rolls 47. The guide member 76 is provided with a groove 76^a in which slides the projection 75^a formed on each of the guide blocks 75 and when the blocks 75 have been adjusted to the desired position they are secured in place by clamping bolts 81 which pass vertically through the guiding blocks and engage undercut slots 82 formed in the guide member 76. Each guide block 75 is provided with an inturned flange 75^b along its lower edge which serves as a guide for the lateral edge of the metal strip 35. This flange 75^b has the forward portion of its surface inclined as shown at 75^c and the rear portion of the upper surface of this guide flange is substantially horizontal as shown at 75^d. The guide flange 75^b is adapted to cooperate with a cheek plate 85, one of which is mounted on each of the guide blocks 75. The cheek plates 85 are generally similar in

form to the cheek plates 58 mounted on the guide blocks 52 except that the cheek plates 85 are mounted for pivotal adjustment. Each cheek plate 85 is secured to the adjacent guide block 75 by means of a stud 86 about which it is capable of pivotal movement. Each cheek plate has at its rear end a laterally projecting flange 85^a which overlies the adjacent guide block and an adjusting screw 87 passes through each flange 85^a into the guide block so that upon adjustment of this screw, the inclination of the cheek plate 85 about its pivot 86 may be varied. The limit of this pivotal movement is determined by a second stud 88 which passes through an elongated slot 89 in the cheek plate into a threaded hole in the guide block. Each cheek plate 85 has a flange 85^b which extends inwardly over the flange 75^b of the guide block, thus leaving an intervening slot 90 through which the metal strip 35 passes. The vertical dimension of this slot may be varied by adjusting the cheek plate 85. The flange 85^b is continued forwardly and upwardly, being inclined as shown at 85^c and substantially semi-circular as shown at 85^d, thus guiding the forward end of the moving strip of metal into the slot 90. The lateral adjustment of the guide blocks 75 and parts carried thereby is effected by means of two adjusting screws 91, the opposite ends of which are threaded in opposite directions and arranged to have a threaded engagement with the depending ears 92 which are formed on the under side of the guide blocks. The two adjusting screws 91 are located on opposite sides of the guide member 76 and each adjusting screw has a worm wheel 93 secured to the middle part thereof to mesh with one of the worms 94 secured on the longitudinal shaft 95. This shaft is journaled in bearings 96 carried by a bracket 97 attached to the guide member 76 and it is connected by bevel gears 98 with a transverse shaft 99 journaled in bearings 100 carried by the bracket 77 and flanges 78. The shaft 99 has a squared extremity 99^a adapted to be engaged by a wrench for effecting the simultaneous adjustment of the guide blocks 75 toward or from each other after the clamping bolts 81 have been released by the adjustment of the nuts engaging their upper extremities. It will be observed that the guide flanges 75^b and 85^b formed on the guide blocks and cheek plates, respectively, extend rearwardly of the mill in close proximity to the place where the reducing rollers 47 engage the upper and lower surfaces of the metal strip 35, as shown in Fig. 5, thus providing means for guiding the lateral edges of the strip and securing the proper alignment of the edges of the upper and lower superimposed layers, immediately before the strip passes into engagement with the reducing rollers.

65 In practice, the guiding rollers 60 are pref-

erably spaced apart a distance of about $\frac{1}{32}$ of an inch less than the estimated minimum width of the metal strip being rolled in a particular series of operations with a fixed adjustment of the blocks 52 and, with this spaced relation of the guide rollers 60, the spaced relation of the vertical faces of the guide blocks 52 should preferably be about one-fourth of an inch more, and the spaced relation of the vertical faces of the guide blocks 75 should preferably be about one thirty-second of an inch more than the shortest distance between the peripheral surfaces of the bottoms of the grooves of the opposite guide rollers 60. If a metal sheet or strip comes to the guide rollers 60 which is wider than the space between them, it will usually bow upwardly, as shown in Fig. 9, or downwardly since it is then relatively thin or one layer may bow upwardly and the other downwardly. Although the fixed guides are slightly farther apart, they are sufficiently close to the edges of the metal strip to maintain the proper alignment of the layers of the strip as the doubled end thereof passes into engagement with the reducing rollers 47. The guide rollers 60 are positively driven and are preferably connected to the reducing rolls of the next preceding set so that their speed is proportional to the speed of the oncoming doubled strip rather than being proportional to the speed of the further reduced strip after it has passed through the next following reducing roll. For this purpose the transverse shaft 65 which drives the rollers 60 is actuated by the mechanism shown particularly in Figs. 7 and 8. Each shaft 65 is connected to an extension 101 through a ratchet wheel 102 and a disk 103 carrying a pivoted pawl 104 which engages the teeth of the ratchet wheel, as illustrated in Figs. 7 and 10. The disk 103 is fixed on the shaft 101 while the ratchet wheel 102 is fixed on the shaft 65 and the pawl 104 is actuated by a spring 105 to engage the teeth of the ratchet wheel so that when the shaft 101 is actuated it drives the shaft 65 through the ratchet teeth while at the same time permitting the shaft 65 to rotate at a higher rate of speed in case the rollers 60 tend to rotate at a higher rate under the influence of the moving strip of metal. The shaft 101 is connected by gears 106 with another shaft 107 having bearings carried by the casing of the gear box 48 and the outer end of this shaft 107 has fixed thereon a sprocket gear 108 arranged to mesh with a driving chain 109 which is actuated by another sprocket gear 110 fixed on the shaft 49^a of the pinion gears which drive the next preceding set of reducing rolls. In this way, the rollers 60 of the guiding means 50 are driven at the proper speed to engage the edges of the oncoming strip of metal which after passing through one set of reducing rolls is partially reduced in thickness, as

shown in Fig. 8, and then, after passing through the next succeeding set of reducing rolls, is still further reduced in thickness. The peripheral speed of the guide rollers 60 of one set, therefore corresponds to the peripheral speed of the reducing rollers which engage the metal strip, or layers, of the same thickness. The speeds of the driving motors 49 are regulated to compensate for this difference in the necessary peripheral speeds of the reducing rollers and of the guide rollers and, in practice, these speeds are preferably so regulated that the reducing rolls of one set will tend to cause the metal strip 35 to bow upwardly between two sets of reducing rolls, as shown at 112 in Fig. 8, thus preventing any tendency for a tension to be set up in the metal strip between two sets of rolls. Notwithstanding this possible upward bowing of the longitudinal strip of metal, as it passes through the reducing rolls by which the finishing operations are performed, the metal strip is properly directed into the guide rollers 60 of each set by the action of the tapered guiding means carried by the guiding blocks 52.

Although one form of the improved guiding means of the present invention has been shown and described by way of illustration 30 in connection with a particular arrangement of rolling mill apparatus, it will be understood that the invention may be adapted for use with various forms of apparatus in rolling mills and may be constructed in various 35 forms within the scope of the appended claims.

I claim:

1. The combination in apparatus for manufacturing metal sheets and strips of sheet gauges, of means for reducing a slab to form 40 a strip of sheet bar thickness, means for doubling said strip, finishing rolls for further reducing said doubled strip, and positively driven guiding means located adjacent to said 45 finishing rolls for engaging and guiding the lateral edges of said doubled strip.

2. The combination in apparatus for manufacturing metal sheets and strips of sheet gauges, of means for forming a pack of superimposed metal layers, a pair of rolls adapted 50 to reduce said metal pack, rotary guiding means located adjacent to said rolls for engaging the sides of said pack, means for driving said rotary guiding means, and stationary 55 guiding means having a greater spaced relation than said rotary guiding means for engaging the lateral edges of said pack.

3. The combination in apparatus for manufacturing metal sheets and strips of sheet 60 gauges, of means for forming a pack of superimposed metal layers, of a pair of rolls adapted to reduce said metal pack, rotary guiding means located adjacent to said rolls for engaging the sides of said metal layers, and 65 normally stationary guiding means extend-

ing into the converging space adjacent the line of contact of said rolls with said pack for guiding said pack edgewise between said rolls.

4. The combination in apparatus for manufacturing metal sheets and strips of sheet gauges, of means for forming a pack of superimposed metal layers, a pair of rolls adapted to reduce said metal pack, means for moving 70 said pack to said rolls, movable positively driven guiding means adapted to engage the lateral edges of said pack in advance of said rolls, and normally stationary guiding means adapted to engage said pack on its edges between said movable guiding means and said 75 rolls.

5. The combination in apparatus for manufacturing metal sheets and strips of sheet gauges, of means for forming a strip of sheet bar thickness, means for doubling said strip, 80 a pair of rolls adapted to reduce said doubled strip, rotary guiding means located adjacent to said rolls for engaging the sides of said doubled strip, normally stationary guiding means extending into the converging space 85 adjacent the line of contact of said rolls with said doubled strip edgewise for guiding said doubled strip between said rolls, and means for adjusting the spaced relation of said guiding means.

6. The combination in apparatus for manufacturing metal sheets and strips of sheet gauges, of means for forming a strip of sheet bar thickness, means for doubling said strip, 90 a pair of rolls adapted to reduce said doubled strip, movable guiding means adapted to engage the lateral edges of said doubled strip in advance of said rolls, normally stationary guiding means adapted to engage said doubled strip on its edges between said movable guiding means and said rolls, and means for adjusting the spaced relation of said 95 movable guiding means independently of said normally stationary guiding means.

7. The combination in apparatus for manufacturing metal sheets and strips of sheet gauges, of means for doubling a metal strip of sheet bar thickness, a set of rolls for reducing said doubled strip, rotary guiding means for engaging the lateral edges of said 100 doubled strip in advance of said rolls, normally stationary guiding means in advance of said rotary guiding means for engaging the lateral edges of said doubled strip, and means for simultaneously adjusting the 105 spaced relation of said rotary guiding means and said normally stationary guiding means.

8. The combination in apparatus for manufacturing metal sheets and strips of sheet 110 gauges, of a set of rolls for reducing a metal pack, means for moving said pack to said rolls, rotary guiding means engaging said pack in advance of said rolls, and means for driving said rotary guiding means with 115 120 125 130

a speed proportional to the speed of travel of said pack towards said rolls.

9. The combination in apparatus for manufacturing metal sheets and strips of sheet gauges, of a plurality of sets of rolls for successively engaging and reducing a metal pack, means for driving said rolls, rotary guiding means for engaging the metal pack in advance of each set of said rolls, and means for driving said rotary guiding means with a speed proportional to the speed of the next preceding set of said rolls.

10. The combination in apparatus for manufacturing metal sheets and strips of sheet gauges, of a plurality of sets of rolls for successively engaging and reducing a metal pack, means for driving said rolls, rotary guiding means for engaging the metal pack in advance of each set of said rolls, means for driving said rotary guiding means with a speed proportional to the speed of the next preceding set of said rolls, and means for permitting said rotary guiding means to move with a speed greater than the speed of its driving means.

11. The combination in apparatus for manufacturing metal sheets and strips of sheet gauges, of guiding means for engaging the under side and the top edges of a moving metal strip, normally stationary guiding means adapted to engage the lateral edges of said strip, and rotary guiding means adapted to engage the lateral edges of said strip.

12. The combination in apparatus for manufacturing metal sheets and strips of sheet gauges, of means for moving a metal pack, normally stationary guiding means adapted to engage the lateral edges of said pack, rotary guiding means adapted to engage the edges of said pack beyond said stationary guiding means for guiding said pack beyond said stationary guiding means.

13. The combination in apparatus for manufacturing metal sheets and strips of sheet gauges, of means for moving a doubled metal strip, normally stationary guiding means adapted to engage the lateral edges of said doubled strip, rotary guiding means adapted to engage the edges of said doubled strip beyond said stationary guiding means, additional normally stationary guiding means for guiding said doubled strip beyond said rotary guiding means, and a pair of reducing rolls adapted to engage said doubled strip immediately after it emerges from said last named guiding means.

14. The combination in apparatus for manufacturing metal sheets and strips of sheet gauges, of means for moving a metal strip, guide blocks arranged to engage the lateral sides of said strip, a guiding member carried by each of said blocks above a

lateral edge of said strip, and guiding means engaging the under side of said strip.

15. The combination in apparatus for manufacturing metal sheets and strips of sheet gauges, of means for moving a metal strip, guide blocks arranged to engage the lateral sides of said strip, a guiding member carried by each of said blocks above a lateral edge of said strip, and means for adjusting each of said guide members to vary its spaced relation with respect to said metal strip.

16. The combination in apparatus for manufacturing metal sheets and strips of sheet gauges, of a pair of guide blocks adapted to engage the lateral edges of a doubled metal strip during its movement, guide members carried by each of said guide blocks for engagement with the upper and lower surfaces of said doubled strip adjacent the lateral edges thereof, and rotary guiding means adapted to engage the lateral edges of said doubled strip as it emerges from said guide members.

17. The combination in apparatus for manufacturing metal sheets and strips of sheet gauges, of a pair of guide blocks adapted to engage the lateral edges of a doubled metal strip during its movement, guide members carried by each of said guide blocks for engagement with the upper and lower surfaces of said doubled strip adjacent the lateral edges thereof, rotary guiding means adapted to engage the lateral edges of said doubled strip as it emerges from said guide members, and means for positively driving said rotary guiding means.

18. The combination in apparatus for manufacturing metal sheets and strips of sheet gauges, of means for guiding the movement of a doubled metal strip comprising a pair of guide blocks adapted to engage the lateral edges of said doubled strip, a shaft journaled in each of said guide blocks, and a grooved guide roller mounted on each of said shafts for engagement with a lateral edge of said doubled strip.

19. The combination in apparatus for manufacturing metal sheets and strips of sheet gauges, of means for guiding the movement of a doubled metal strip comprising a pair of guide blocks adapted to engage the lateral edges of said doubled strip, a shaft journaled in each of said guide blocks, a grooved guide roller mounted on each of said shafts for engagement with a lateral edge of said doubled strip, and means for driving said guide rollers at the same speed.

20. The combination in apparatus for manufacturing metal sheets and strips of sheet gauges, of means for guiding the movement of a doubled metal strip comprising a pair of guide blocks adapted to engage the lateral edges of said doubled strip, a shaft journaled in each of said guide blocks, a

grooved guide roller mounted on each of said shafts for engagement with a lateral edge of said doubled strip, and means for adjusting said guide blocks transversely to the path of movement of said strip for varying their spaced relation.

21. The combination in apparatus for manufacturing metal sheets and strips of sheet gauges, of means for guiding the movement of a doubled metal strip comprising a pair of guide blocks adapted to engage the lateral edges of said doubled strip, a shaft journaled in each of said guide blocks, a grooved guide roller mounted on each of said shafts for engagement with a lateral edge of said doubled strip, means for adjusting said guide blocks transversely to the path of movement of said doubled strip for varying their spaced relation, and means for clamping said guide blocks in adjusted position.

22. The combination in apparatus for manufacturing metal sheets and strips of sheet gauges, of means for guiding the movement of a doubled metal strip comprising normally stationary guiding means for engaging the lateral edges of said doubled strip, movable guiding means for engaging the lateral edges of said strip after it passes said first-named guiding means, and means for independently adjusting the lateral spaced relation of each of said guiding means.

23. The combination in apparatus for manufacturing metal sheets and strips of sheet gauges, of means for guiding the movement of a doubled metal strip comprising normally stationary guiding means for engaging the lateral edges of said doubled strip, movable guiding means for engaging the lateral edges of said strip after it passes said first-named guiding means, other normally stationary guiding means for engaging the lateral edges of said doubled strip as it passes from said movable guiding means, and means for adjusting the lateral spaced relation of each of said guiding means independently of the corresponding adjustment of each of said other guiding means.

24. The combination in apparatus for manufacturing metal sheets and strips of sheet gauges, of means for guiding the movement of doubled metal strips comprising normally stationary guiding means having a spaced relation slightly greater than the width of the doubled strips, and rotary guiding means engaging the lateral edges of said doubled strips as they pass from said first-named guiding means, said rotary guiding means having a spaced relation slightly less than the average width of the doubled strips passing therethrough.

25. The combination in apparatus for manufacturing metal sheets and strips of sheet gauges, of means for guiding the movement of doubled metal strips comprising a

pair of grooved rollers adapted to engage the lateral edges of the doubled strips and having a spaced relation slightly less than the average width of the doubled strips, and normally stationary guiding means having a greater spaced relation than said grooved rollers and adapted to receive said doubled strips from said rollers.

26. The combination in apparatus for manufacturing metal sheets and strips of sheet gauges, of means for guiding the movement of doubled metal strips comprising a pair of grooved rollers adapted to engage the lateral edges of the doubled strips and having a spaced relation slightly less than the average width of the doubled strips, normally stationary guiding means having a greater spaced relation than said grooved rollers and adapted to receive said doubled strips from said rollers, and reducing rollers arranged to receive said doubled strips from said normally stationary guiding means.

27. The combination in apparatus for manufacturing metal sheets and strips of sheet gauges, of a pair of guide blocks spaced apart to receive a metal strip between them, cheek plates mounted on said guide blocks, and means for adjusting said cheek plates on said guide blocks.

28. The combination in apparatus for manufacturing metal sheets and strips of sheet gauges, of guiding means comprising parts adapted to engage the under side and the lateral edges of a metal strip, cheek plates adapted to guide the upper sides of said metal strip, and means for adjusting said cheek plates angularly with respect to said guiding means.

In testimony whereof, I have subscribed my name.

RALPH H. NORTON.
